UNITED STATES PATENT OFFICE.

LOREN W. DARLING, OF SYCAMORE, ILLINOIS. ASSIGNOR OF ONE-HALF TO ALBERT E. HAMMERSCHMIDT, OF SYCAMORE, ILLINOIS.

BOX MACHINE.

1,422,544.

Specification of Letters Patent. Patented July 11, 1922.

Application filed January 27, 1922. Serial No. 532,206.

To all whom it may concern:

Be it known that I, LOREN W. DARLING, a citizen of the United States, and a resident of Sycamore, De Kalb County, and State of Illinois, have invented certain new and useful Improvements in Box Machines, of which the following is declared to be a full, clear, and exact description.

This invention relates to box machines, and more particularly to machines for applying pressure to the flaps (after glue has been applied to them) of cartons, such as pasteboard, cardboard or strawboard boxes.

The cartons with which this machine has to do, are made in the form of tubular articles of rectangular form, provided with flaps at both ends, that have to be folded down and glued together to close the ends of the carton or box. The machine forming the subject matter of this specification has been designed for use in sealing one end of the cartons, that is to say, the end which forms the bottom of the carton or box, and one of its principal objects is to provide means to insure the formation of square corners for the box. Another object is to provide a machine which will occupy comparatively small space and has a capacity for having a large number of boxes at a given time. Another object is to provide a machine which is simple in construction and comparatively inexpensive to manufacture and is highly efficient for the purpose for which it is intended. The invention consists in the several novel features of construction, arrangement and combination of parts hereinafter fully set forth and claimed.

The invention is clearly illustrated in the accompanying drawings, in which:

Fig. 1 is a plan of a box machine embodying a simple form of the present invention; Fig. 2 is a view partly in side elevation and partly in vertical section thereof, the line of section being indicated at 2-2 in Fig. 1; Fig. 3 is a side elevation of one of the pressure heads of the machine; Fig. 4 is a detail, vertical, cross-section, taken on the line 4-4 of Fig. 3; Fig. 5 is a view similar to Fig. 4, but showing the upper pressure block in raised position, and Fig. 6 is a perspective view of a carton or box, showing two of the flaps folded down.

Referring to said drawings, the reference character 10 designates a base of rectangular

form mounted upon rollers 11, whereby the machine may be readily moved about from place to place. Said base is formed of lengthwise and crosswise extending frame members 12, suitably secured together, and a top base member 13. Secured to and extending up from said base is a centrally located stationary post or standard 14, which extends through the top base member 13 and is secured thereto by nuts 15, which are threaded upon the lower threaded end of the post 14 and are screwed up against the upper and lower faces of the top base member 13. Rotatively mounted on said base 10 is a turntable 16, which conveniently may comprise two spaced plates 17, and radially extending arms 18 secured between said plates by bolts 19. The turntable rotates about the post 14 and between the turntable 16 and base 10 are interposed anti-friction bearings 20. The particular construction of the turntable just described is immaterial, but it serves for the purpose of illustration.

Extending up from said turntable are lower pressure heads, which may comprise lower pressure blocks 22 and posts or pedestals 21, which are arranged circumferentially about the axis of rotation of the turntable. Said posts or pedestals 21 are secured to the outer ends of the arms 18 of the turntable, and support, at their upper ends, the rectangular lower pressure blocks 22, which are made of the proper size and shape to fit nicely within the cartons when the latter are slipped over them. Said blocks 22 may be loosely supported on the posts 21, if desired, and, they may be provided with downwardly projecting stems or lugs 23 (see Figs. 4 and 5) which enter hollow portions of the posts and hold them in place thereon. The blocks 22 are also formed with transversely extending grooves 24 in their upper faces, which are adapted to receive any surplus glue or adhesive material, which may drop from the flaps while under pressure.

Associated with each lower pressure head 22 is an upper pressure head 25, which has an upper pressure block 26, that may be brought over and above the lower pressure block 22. The several upper pressure heads are similar in construction and consequently a description of one will suffice for all.

Each upper pressure head is pivotally secured to the turntable 16, whereby the upper

- pressure block 26 thereof may be swung over an associated lower pressure block 22, and in the form of the invention illustrated, the upper pressure head contains two parallel supporting rods 27, the lower ends of which are secured to a shaft 28 which extends transversely through the post 21 and has collars 29 secured to it that bear against the post and prevent endwise movement of the shaft.
- 10 The rod 27 and shaft 28 may be connected together by T fittings 30, as shown, and the rods 27 are threaded and have nuts 31 on their threaded ends, whereby said rods 27 may be adjusted lengthwise of themselves
- 15 in the T fittings, to regulate the distance between the pressure block 26 and the pressure block 22, when one is above the other and before the upper one is lowered.

The pressure block 26 is removably se-

- 20 cured to the underside of a pressure block supporting plate 32 by bolts, which plate is formed with bosses 33 upon its opposite ends, that are slidably mounted on the rods 27. From this, it will be understood that 25 the plate 32 with its attached pressure block 26 is slidably mounted on the swinging rods 27.

Above the pressure block supporting plate 32 is a pressure applying device, which, as 30 shown, comprises a pressure lever 34 rotatively mounted on a shaft 35 which is secured in T fittings 36 that are adjustably mounted on the upper ends of the swinging rods 27 and secured thereon by nuts 37, threaded on 35 the rods 27. The plate 32 and its block 26 are supported from the lever 34 by a bail 40. The pressure lever 34 is formed with a curved bearing face 38, which is eccentrically disposed with respect to the axis of the 40 shaft 35, whereby when the lever 34 is swung from the position illustrated in Fig. 5, to that illustrated in Fig. 4, the eccentric bearing face 38 will be forcibly brought into contact with the plate 32, and the 45 latter, with its pressure block 26, will be forcibly brought down upon the flaps of a carton held between the pressure blocks. The pressure lever 34 has a handle 39 whereby 50 it is operated and whereby the entire upper pressure head is operated in applying pressure to the flaps of cartons. A head rest 41 is secured upon the upper end of the central post 14 in position to act as a stop against which the movable pressure heads 55 may rest when thrown back, out of operative position.

To insure the formation of square corners for the cartons, side engaging rollers 42 are provided on the upper pressure head, 60 which rollers are arranged to engage with two opposite sides of the cartons. Said rollers 42 are mounted on pins or stems 43, that form the joint between toggle links 44, 45, which are pivotally connected to the supporting plate bosses 33, and to collars 46

that are secured on the supporting rods 27. The collars 46 rest on coiled springs 47 which are supported by collars 48, fast on the rods 27, and said springs 47 allow the rollers 42 to yield slightly in case of slight 70 variations in the thickness of the carton walls. When the upper pressure board is raised from the position seen in Fig. 3, the toggle links 44 and 45 straighten out and move the rollers 42 away from the sides of 75 the carton, thereby permitting the upper pressure head to be freely swung back and forth without interfering with the carton. On the back of the block 26 is a downwardly projecting shoulder 49 which is arranged to engage the lower pressure block 22 or an interposed carton wall, to properly 80 position the upper pressure block thereabove.

In the operation of the machine, and 85 assuming that all of the movable pressure heads are thrown back and resting against the head rest 41, the attendant places a tubular carton A, (see Fig. 6) over a pressure block 22, folds down two opposite end flaps 90 a on the block 22, applies glue or other adhesive material to said flaps, and folds down the other two flaps a'. He then takes hold of the handle 37, draws the upper or movable pressure head forward until the shoulder 49 strikes the block 22, or rather the interposed wall of the carton, which brings the upper pressure block 26 directly over the lower pressure block 22, and the interposed folded flaps a, a'. He then swings 100 back the lever 34 from the position shown in Fig. 5 to that shown in Fig. 4, thereby lowering the upper pressure block upon the flaps and finally pressing it firmly down thereon, as the major diameter of the eccentric portion of the lever reaches the plate 32. In this position, the flaps are held under pressure by the lever 34, which automatically becomes locked in place as the high 105 part of the eccentric face reaches the plate. 110

The attendant thereupon turns the turntable until the next adjacent pressure head comes in front of him, and repeats the operation on another carton. By the time the first carton has made a complete circuit and reaches the attendant, the glue has had time to set and the attendant swings forward the lever 34 of the upper pressure head (holding the finished carton), thereby raising the upper pressure block, after which he swings 115 back the entire upper or movable pressure head until it rests against the head rest 41, whereupon he removes the carton from the lower pressure block and repeats the operations with other cartons. 120

It is to be observed that the pressure blocks are readily removable, which makes it possible to substitute pressure blocks of other dimensions therefor. Consequently, by using pressure blocks of the proper di- 125

mensions, various sizes of cartons may be operated on by the machine.

More or less variation of the exact details of construction is possible without departing from the spirit of this invention; I desire, therefore, not to limit myself to the exact form of the invention shown and described, but intend in the following claims, to point out all of the invention disclosed herein.

10 I claim as new and desire to secure by Letters Patent:

1. In a box machine, the combination of a base, a turntable rotatively mounted thereon, and having a plurality of lower pressure heads extending up therefrom, circumferentially about its axis of rotation, and upper pressure heads, one co-operating with each lower pressure head and fulcrumed on said turntable, said upper pressure heads having pressure blocks capable of being moved over said lower pressure heads and movable lengthwise of said head, and pressure levers for clamping said pressure blocks upon the folded flaps of a carton.

2. In a box machine, the combination of a base, a turntable rotatively mounted thereon, and having a plurality of lower pressure heads extending up therefrom, circumferentially about its axis of rotation, and upper pressure heads, one co-operating with each lower pressure head and fulcrumed on said turntable, said upper pressure heads having pressure blocks capable of being moved over said lower pressure heads and pressure levers pivotally supported on said upper pressure heads and having eccentric bearing faces arranged to be brought into forcible engagement with said upper pressure blocks, where- 40 by folded flaps of cartons may be held under pressure between said pressure blocks.

3. In a box machine, the combination of a base, a turntable rotatively mounted thereon, a plurality of posts extending up from said turntable, and arranged circumferentially about its axis of rotation, lower pressure blocks removably secured on said posts, and upper pressure heads, one for each lower pressure block, each upper pressure head having an upper pressure block, and being fulcrumed on an associated post, whereby said upper pressure block may be moved over a lower pressure block, and pressure levers mounted on said upper pressure heads 55 and arranged to be brought forcibly into engagement with said upper pressure blocks, to apply pressure upon folded flaps of a carton held between said upper and lower pressure blocks.

60 4. In a box machine, the combination of a base, a turntable rotatively mounted thereon, a plurality of circumferentially arranged lower pressure heads supported by said turntable, each head having a rectangular lower pressure block, upper pressure head frames,

one associated with each lower pressure head and fulcrumed thereon, an upper pressure block slidably mounted on each frame, a pressure lever carried by said frame, and a block supporting connection between each upper pressure block and its associated pressure lever.

5. In a box machine, the combination of a base, a turntable rotatively mounted thereon, a plurality of circumferentially arranged lower pressure heads supported by said turntable, each head having a rectangular lower pressure block, upper pressure head frames, one associated with each lower pressure head and fulcrumed thereon, an upper pressure block slidably mounted on each frame, an eccentric pressure member carried by said frame and having a handle, and a block supporting connection between each upper pressure block and its associated pressure member.

6. In a box machine, the combination of a base, a central post extending up therefrom, a head rest on said post, a turntable rotatively mounted on said base, lower pressure heads secured to and extending up from said turntable, said lower pressure heads having lower pressure blocks and being circumferentially arranged about the turntable, and upper pressure heads fulcrumed on said lower pressure heads, and having upper pressure blocks arranged to be brought into forcible contact with the folded flaps of a carton held between said pressure blocks, and said upper pressure heads being capable of being swung back against said head rest to uncover said lower pressure blocks.

7. In a box machine, a lower pressure head, having a post and a rectangular lower pressure block secured on its upper end, a frame fulcrumed on said post and having two parallel guide rods, an upper rectangular pressure block slidably mounted on said guide rods, and a pressure lever for said upper pressure block, carried by said frame, and having a handle whereby said lever and frame are manipulated.

8. In a box machine, a lower pressure head, having a post and a rectangular lower pressure block secured on its upper end, a frame fulcrumed on said post and having two parallel guide rods, an upper rectangular pressure block slidably mounted on said guide rods, a pressure lever for said upper pressure block, carried by said frame, and having a handle whereby said lever and frame are manipulated, and a bail connecting said upper pressure block and lever.

9. In a box machine, a post, a rectangular lower pressure block supported thereon, a frame fulcrumed on said post, an upper rectangular pressure block slidably mounted on said frame, a pressure lever for said block, laterally movable side engaging rollers supported on said frame and auto-

matic means for thrusting them against the sides of a carton held on said lower pressure block.

10. In a box machine, a post, a rectangular lower pressure block supported thereon, a frame fulcrumed on said post, an upper rectangular pressure block slidably mounted on said frame, a pressure lever for said block, laterally movable side engaging rollers, toggle links supporting said rollers at the joint between the links, the upper ends of said toggle links being connected to said upper pressure block, and being movable relative to the lower ends of said toggle links.

11. In a box machine, a post, a rectangular lower pressure block supported thereon, a frame fulcrumed on said post, an upper rectangular pressure block slidably mounted on said frame, a pressure lever for said block, laterally movable side engaging roll-

ers, toggle links supporting said rollers at the joint between the links, the upper ends of said toggle links being connected to said upper pressure block, and collars on the 25 frame, to which the lower ends of said toggle links are connected.

12. In a box machine, a post, a rectangular lower pressure block supported thereon, a frame fulcrumed on said post, an upper 30 rectangular pressure block slidably mounted on said frame, a pressure lever for said block, laterally movable side engaging rollers, toggle links supporting said rollers at the joint between the links, the upper ends 35 of said toggle links being connected to said upper pressure block, movable collars on the frame, to which the lower ends of said toggle links are connected, collars stationarily secured to the frame and coiled springs between said collars.

LOREN W. DARLING.
